UNITED STATES PATENT OFFICE

147,106

DESIGN FOR A HOUSING FOR ELECTRICAL APPARATUS

Philip Bradstock, Elyria, and Simon S. Maier,
Lorain, Ohio, assignors to Guaranteed Products,
Wellington, Ohio, a partnership consisting of
Philip Bradstock and Simon S. Maier

Application November 14, 1945, Serial No. 123,724

Term of patent 3½ years

(Cl. D26—5)

To all whom it may concern:

Be it known that we, Philip Bradstock and Simon S. Maier, citizens of the United States of America, residing at Gulf Farms, Elyria, county of Lorain, State of Ohio, and Lorain, county of Lorain, State of Ohio, respectively, have invented a new, original, and ornamental Design for a Housing for Electrical Apparatus, of which the following is a specification, reference being had to the accompanying drawings, forming a part thereof.

Fig. 1 is a front perspective view of a housing for electrical apparatus showing our new design;

Fig. 2 is a rear perspective view; Fig. 3 is a top plan view, and Fig. 4 is an end view thereof.

We claim:

The ornamental design for a housing for electrical apparatus, as shown.

PHILIP BRADSTOCK.
SIMON S. MAIER.
